FOLDING LOOP ANTENNA

Filed Aug. 25, 1924

UNITED STATES PATENT OFFICE.

MAURICE W. STAVRUM, ROBERT L. OLSON, AND WALLACE H. BERRY, OF CHICAGO,
ILLINOIS.

FOLDING-LOOP ANTENNA.

Application filed August 25, 1924. Serial No. 734,021.

To all whom it may concern:

Be it known that we, MAURICE W. STAVRUM, ROBERT L. OLSON, and WALLACE H. BERRY, citizens of the United States, and 5 residents of Chicago, in the county of Cook and State of Illinois, have invented a new and useful Improvement in a Folding-Loop Antenna, of which the following is a full, clear, and exact description.

10 Our invention relates to improvements in folding loop antenna, and it consists in the combinations, constructions, and arrangements herein described and claimed.

An object of our invention is to provide 15 a folding loop antenna which may be folded up or extended quickly and easily, and in which the wires are held normally taut when the loop is extended.

A further object of our invention is to 20 provide an antenna of the character described in which a bank-winding of the turns of wire thereupon is accomplished thereby reducing the distributed capacity of the antenna to a minimum.

25 A further object of our invention is to provide a device of the character described in which an especially novel arrangement of parts is provided by means of which bank-winding of the turns of wire on the 30 antenna does not in any way hinder the symmetrical arrangement of the turns in the appearance of the loop. This is accomplished by the provision of a double comb at the lower arm of the supporting frame.

35 A further object of our invention is to provide a device of the character described in which a novel arrangement of the wire comprising the loop is accomplished so as to materially reduce the width of the loop.

40 A further object of our invention is to provide a device that is extremely simple in construction, durable, and that is thoroughly practical for the purpose intended.

45 Other objects and advantages will appear in the following specification, and the novel features of the invention will be particularly pointed out in the appended claims.

Our invention is illustrated in the accompanying drawings forming a part of this 50 application in which:

Figure 1 is a front elevation of an embodiment of our invention,

55 Figure 1 is an enlarged fragmentary elevation of a part of the mechanism shown in Figure 1,

Figure 3 is an enlarged view along the line 3—3 of Figure 1,

Figure 4 is an enlarged elevation of a 60 part of the mechanism shown in Figure 1,

Figure 5 is a sectional view along the line 65 5—5 of Figure 4.

In carrying out our invention we make use of a base member 1, having a metal plate 2 centrally located on the upper surface 70 thereof, and provided with a socket in the center of the plate extending into the base portion 1, as shown in dotted lines in Figure 4. A pair of binding posts 4 and 5 are mounted upon the base member 1.

Our improved folding loop antenna consists in a folding frame, combs carried by 75 said frame, a flexible wire supported by the combs.

The folding frame consists in four normally radial arms, 6, 7, 8, and 9, in Figure 1. The arm 6 is the longest of the four arms, and is disposed at the lower end of the frame. A tubular metal sheath 10 encompasses the lowermost end of the arm 6 and 80 a depending shaft 11 (see dotted lines) is provided at the lower extremity of the arm. This shaft is arranged to be received in the socket 3 so that the frame may turn freely upon the base 1.

85 The arms 6 and 8 are hingedly secured to one another by the provision of a link 12 which is constructed of fiber or bakelite, pivotally connected with the arms 6 and 8 by the provision of shafts 13 extending 90 through bifurcated portions 14 of the arms 6 and 8, in which the link 12 is partially received.

A metal hub member 15, forming a hub 95 for the arms 6 to 9 inclusive when the frame is extended, is slidably mounted upon the normally aligned arms 6 to 8.

When the hub member 15 is in the position shown in Figure 2 and is arrested from further downward movement by means of a 100 stop 16 secured to the arm 6, the frame is in position for final contraction when the arm 8 is held downwardly against the arm 6.

When the hub member 15 is in the position shown in Figure 1, movement of the 105 arms 6 and 8 relative to one another is precluded and these arms are held in rigid axial alignment with one another as long as the hub member remains in this position. This is due to the fact that the hub member 110

15 is provided with a tubular portion 17 and thus mar the symmetrical arrangement through which the arms 6 and 8 are free to move and which partially receives one of the arms when the hub is in the position shown in Figure 1.

The arms 7 and 9 are pivotally mounted upon the hub member by the provision of bolts 18 and 19, respectively.

When the hub member is in the position shown in Figure 2, the arms 7 and 9 may assume the position shown in this figure but when the hub member is elevated to its normal position the arms 7 and 9 must assume positions diametrically opposite and in axial alignment transverse with the alignment of the arm 8 so as to form a perfect cross arm.

Because of the bank-frame. A stop member 20, similar to the stop member 16, is provided on the arm 8 to limit the upward movement of the hub 15, and a spring pressed ball 21 is disposed upon the arm 6 and arranged to engage with an opening 22 through the side wall of the tubular portion 17 of the hub 15 when the hub 15 is in the position shown in Figure 1.

Means for supporting a bank-wound flexible antenna wire is provided by combs 23 carried at the outer end of the arms 7, 8 and 9. These combs are constructed of

bakelite or other suitable material, and have seven short slots 24 at equal distances from one another extending toward the hub 15. Seven longer slots 25 disposed between the slots 24 respectively are also provided.

The difference between the depth of the slots 24 and 25 determines the distance between the inner and outer portion of the double winding, as shown in Figure 4. In order to permit the bank-winding of the wire upon the combs 23 without destroying the symmetrical appearance and arrangement of the winding, we employ two combs 26 and 27 identical in structure which are secured at

each side of the arm 6 adjacent to the hub 15, that the portions of the winding between the combs 26 and 27 and the combs 23

are provided in the comb on the opposite side of the arm 6; so that the winding is virtually separated by the arm for a short portion of its length between the arms 7 and 9. A single wire having its terminations at 28 and 29 on the combs 26 and 27 respectively, is wound upon the combs 23, 26, 7 and 27, so as to form a banked winding which is accomplished by crossing from the innermost winding to the outermost winding overlapping of the turns on this portion of 31 between the combs 26 and 27, as shown in Figures 4 and 5.

If it were not for this construction the crossing from the innermost winding to the outermost winding would necessarily occur between the arms 6 and 9 or between any other of the arms,

of the winding. By confining the crossing of the wire to two points closely adjacent to one another we have greatly enhanced the appearance, as well as the efficiency of the

loop.

From the foregoing description of the various parts of the device the operation

thereof may be readily understood. Nor-

mally our improved loop rests in the position shown in Figure 1 with the terminals 28 and 29 connected with the binding posts 4 and 5 respectively, so that radio apparatus

may be in turn connected with the binding posts 4 and 5 and receive incoming signals inter-

cepted by the antenna. Because of the bank-frame.

winding of the wire of the loop, the dis-

tribution capacity of the loop will be reduced to a minimum and the loop will therefore

function with a high degree of efficiency.

The device will be pleasing to the eye because of the perfect symmetry of the arms 6 to 9 inclusive, and the fact that the wind-

ings upon the combs are uniform through-

out. When it is desired to collapse the loop,

as in carrying from one point to another or the like, it will be necessary to manually

lower the hub 15 to the position shown in Figure 2, i. e., against the stop member 16.

This will permit the arm 8 to be moved substantially parallel with the arm 6; by virtue

of the link 12. The arms 7 and 9 will incline upwardly as shown in Figure 2 so that

the frame will collapse into a space slightly

longer than the length of the arm 6.

Another most important advantage attained by the structure and arrangement of the double winding, as shown in Figure 4. In the wires in our improved loop antenna is

order to permit the bank-winding of the wire that a maximum inductance in the winding

upon the combs 23 without destroying the symmetry and arrangement of the winding, we employ two combs 26 and 27.

identical in structure which are secured at

each side of the arm 6 adjacent to the hub member 15, that the portions of the winding be-

tween the combs 26 and 27 and the combs 23

are provided in the comb on the opposite side of the arm 6; so that the winding is

virtually separated by the arm for a short portion of its length between the arms 7 and 9. A single wire having its terminations at 28 and 29 on the combs 26 and 27 respectively, is wound upon the combs 23, 26, 7 and 27, so as to form a banked winding which is accomplished by crossing from the innermost winding to the outermost winding overlapping of the turns on this portion of 31 between the combs 26 and 27, as shown in Figures 4 and 5.

If it were not for this construction the crossing from the innermost winding to the outermost winding would necessarily occur between the arms 6 and 9 or between any other of the arms,

1. A loop antenna of the character de-

scribed comprising a folding frame, combs

carried by said frame, and a plurality of

turns of wire bank-wound upon said combs.

2. A loop antenna of the character described comprising a frame, combs carried by said frame having a plurality of short and long slots alternately formed therein, and a plurality of turns of wire wound upon said combs and received in said slots, whereby half of the turns may lie concentric with and at a short distance from the remaining half of the turns. 30
- 10 3. A loop antenna of the character described comprising a frame, combs carried by said frame having a plurality of short and long slots alternately formed therein, and a plurality of turns of wire wound upon said combs and received in said slots, whereby every second turn may lie concentric with and at a short distance from the remaining turns. 35
- 15 4. A folding loop antenna of the character described comprising a pair of arms, a link for pivotally connecting said arms to one another in normal axial alignment and permitting the movement of one arm parallel with the remaining arm, at will, a hub member slidably supported upon said arms, 40
- 20 25
- 25

a pair of arms pivotally secured to said hub and extending outwardly from opposite sides of said hub, and combs carried by the outer ends of each of the arms for supporting the flexible wire thereupon. 45

5. A folding loop antenna of the character described comprising a pair of arms, a link for pivotally connecting said arms to one another in normal axial alignment and permitting the movement of one arm parallel with the remaining arm, at will, a hub member slidably supported upon said arms, a pair of arms pivotally secured to said hub and extending outwardly from opposite sides of said hub, and combs carried by the outer ends of each of the arms for supporting the flexible wire thereupon, said hub being permitted to move along said linked arms so as to partially encompass each of the linked arms, thereby precluding movement of said arms relative to one another, at will. 50
